J. J. O'BRIEN

CORE FORMING DEVICE FOR SASH WEIGHT CASTING

Filed April 15, 1922

Fig. 1.

FIG. 2

FIG. 3.

INVENTOR
Joseph J. O'Brien

ATTORNEY
Joseph J. O'Brien

UNITED STATES PATENT OFFICE.

JOSEPH J. O'BRIEN, OF SPRINGFIELD, MASSACHUSETTS, ASSIGNOR TO WILLIAM M. BARNARD, OF SPRINGFIELD, MASSACHUSETTS.

CORE-FORMING DEVICE FOR SASH-WEIGHT CASTING.

Application filed April 15, 1922. Serial No. 553,222.

To all whom it may concern:

Be it known that JOSEPH J. O'BRIEN, a citizen of the United States of America, residing at Springfield, in the county of 55
5 Hampden and State of Massachusetts, has invented certain new and useful Improvements in Core-Forming Devices for Sash-Weight Casting, of which the following is a specification.

10 This invention relates to improvements in core boxes for forming cores for casting sash weights and its leading object is to provide simple means for impressing the weight number on the core capable of rapid insertion and rapid withdrawal from the core box.

15 The improved device for impressing the weight number on the core for forming the sash weight eye consists of a single piece 60
20 device having interfitting companion jaws, one of which carries the weight character or type, the jaws being separable by the spring tension of the connecting portion of the device.

25 With the above and other objects in view the invention consists of certain new and useful constructions and arrangements of parts, clearly described in the following specification and clearly illustrated in the 65
30 following drawings, in which:

Fig. 1 is a vertical sectional view through a core box.

Fig. 2 is an end view of the device.

Fig. 3 is a plan view thereof.

35 Referring to the accompanying drawings illustrating the practical embodiment of the invention 5 designates a core box, which is shown to be formed in one piece, and may be constructed of metal, wood, or any suitable

40 material, and which is provided on its lower end with a tapered stem 6, adapted to fit in a socket or hole 7 formed in a suitable table or other support. This stem is shown to be provided with a plurality of faces to resist 45
45 rotative movement in the socket, which is shaped to fit the stem.

The box 5 is formed with a chamber 5^a in which the sand is packed, the lower end of this chamber tapering, and the side walls

50 8 and 9 of the box being formed with openings 8^a and 9^a, disposed in registration with each other.

Through the registering openings 8^a and 9^a of the core box 5 the forming device 10 is extended. This device consists of a pair 55
5 of interfitting jaws, the upper jaw 11 and the lower jaw 12, each of which is formed U-shaped, in cross section. The two jaws are connected to each other by means of a spring U-shaped portion or loop 13, so that 60
the upper jaw will be forced upwardly against the edge portions 8^b and 9^b of the side walls 8 and 9. On the upper jaw the weight character or type 14 is formed.

The jaws 11 and 12 are provided with 65
stops 15 and 16 so that the insertion of the device in the core box will be limited and the character will come to a position in the center of the core box.

After the device is inserted in the core 70
box sand is placed therein and the tension on the jaws 11 and 12 of the connecting spring is sufficient to prevent the upper jaw yielding under the tamping. When the core box has been filled with sand the worker 75
grips the outer end of the device and by hand pressure closes the two jaws on each other and then withdraws the device, holding the lower jaw against the lower edge portions of the openings of the side walls 80
8 and 9, so that the character will be depressed and may be withdrawn by a sliding action of the whole device. When this is done the core may be taken from the core 85
box.

The core is placed in the mould flask in a manner well known to the art in line with the impression formed by the pattern of the body of the sash weight, and the molten iron 90
poured in the flask.

I claim:

1. A core forming device for sash weight casting consisting of a pair of jaws, one jaw being a U shaped construction and the other jaw having sliding movement therein, the first jaw carrying a casting character thereon, a U shaped spring connecting the jaws to each other and maintaining the same normal interfitting relation and providing a handle for the insertion and removal of the 100
jaws from a core box.

2. A one piece core forming device consisting of a member bent upon itself to provide a pair of opposing jaws, each of said

jaws being provided with longitudinal flanges, the longitudinal flanges of one of the jaws having sliding fit within the longitudinal flange of the other jaw, the bend of 5 the device constituting a spring to maintain a slight outward tension upon the jaws, one of the jaws being provided with a character

on its outer face to engage the core being formed and capable of being disengaged therefrom by pressure exerted upon said 10 jaw.

Signed by me at Springfield.

JOSEPH J. O'BRIEN.
